United States Patent Office

Des. 206,646
Patented Jan. 3, 1967

206,646

TIRE

Aristides Makris, 137 Crescent Ave.,
Plainfield, N.J. 07060

Filed Dec. 28, 1965, Ser. No. 356

Term of patent 14 years

(Cl. D90—20)

Fig. 1

Fig. 2

FIG. 3

FIG. 1 is a fragmentary side elevational view of the side wall of the tire in the shoulder region showing my new design, it being understood that the design is repeated throughout the circumference of the side wall of the tire and that the side not shown is the same in appearance as the side shown;

FIG. 2 is a fragmentary transverse sectional view through the tire substantially on the plane indicated by the line 2—2 of FIG. 1; and

FIG. 3 is a perspective view of a tire embodying my new design, it being understood that the full line portion is repeated throughout the circumference of the tire, shown by means of dot-dash lines.

The dominant features of my design reside in the portions shown in full lines.

I claim:

The ornamental design for a tire, substantially as shown and described.
